[57] **CLAIM**

The ornamental design for an electrical control housing for electric motors, as shown and described.

DESCRIPTION

FIG. 1 is a top plan view of an electrical control housing for electric motors showing my new design;

FIG. 2 is a left-side view of the housing;

FIG. 3 is a front view of the housing;

FIG. 4 is a right-side view of the housing;

FIG. 5 is a rear view of the housing;

FIG. 6 is a bottom view of the housing;

FIG. 7 is a front and upper left perspective view of the housing; and,

FIG. 8 is a rear and lower right perspective view of the housing.

FIG. 5

FIG. 4

FIG. 1

FIG. 2

FIG. 3

FIG. 6

FIG.7

FIG. 8
